SPIRAL FID FOR HAWSERS

James D. McGrew, 8120 Rio Linda Blvd.,
Elverta, Calif. 95626

Filed Mar. 21, 1975, Ser. No. 560,804

Term of patent 14 years

Int. Cl. D8—05

U.S. Cl. D8—14

FIG. 1 is an elevational view of the large-lug side of a spiral fid for hawsers, showing my new design, with the pivotally mounted torque handle in extended position;

FIG. 2 is an elevational view of the opposite, small-lug side and with the torque handle swung through 180°;

FIG. 3 is a top plan view;

FIG. 4 is a bottom plan view;

FIG. 5 is an elevational view of the left-hand side of FIG. 2;

FIG. 6 is an elevational view of the right-hand side of FIG. 2;

FIG. 7 is an elevational view as in FIG. 1 but with the torque handle in folded position;

FIG. 8 is an exploded isometric view showing the spiral spike portion of the fid separated from the externally spiraled hollow sleeve portion, the large lug recess in the sleeve being in longitudinal register with the large lug on the spike and the small lug recess in the sleeve being in

similar register with the small lug on the opposite side of the spike 180° from the large lug in order to match the external spiral on the spike with the external spiral on the sleeve; and

FIG. 9 is a fragmentary sectional view to an enlarged scale, the plane of the section being indicated by the line 9-9 in FIG. 3.

I claim:

The ornamental design for a spiral fid for hawsers, as shown and described.
